CLAIM

The ornamental design for a compression tester, substantially as shown.

DESCRIPTION

FIG. 1 is a front elevational view of a compression tester showing my new design;

FIG. 2 is a left side elevational view thereof, the right side being a mirror image thereto;

FIG. 3 is a rear elevational view thereof.

FIG. 4 is a top plan view thereof; and

FIG. 5 is a bottom plan view thereof.

Fig. 1.

Fig. 2.

Fig. 3.

Fig. 4.

Fig. 5.
